FIGURE 1 is a left end, top and front isometric view of an insulating support for electrical bus bars or similar article, showing one form of our new design.

FIG. 2 is a front elevational view of the form shown in FIG. 1;

FIG. 3 is a side elevational view of the form shown in FIG. 1;

FIG. 4 is a rear elevational view of the form shown in FIG. 1;

FIG. 5 is a cross-sectional view taken on the line 5—5 of FIG. 2;

FIG. 6 is an elevational view of the left-hand end of the form shown in FIG. 1 drawn to an enlarged scale;

FIG. 7 is an elevational view of the right-hand end of the form shown in FIG. 1 drawn to an enlarged scale;

FIG. 8 is a cross-sectional view taken on line 8—8 of FIG. 2 drawn to an enlarged scale;

FIG. 9 is a cross-sectional view taken on 9—9 of FIG. 2 drawn to an enlarged scale;

FIG. 10 is a cross-sectional view taken on the line 10—10 of FIG. 2 drawn to an enlarged scale;

FIG. 11 is a left end, top and front isometric view of an insulating support for electrical bus bars or similar article, showing another form of our new design;

FIG. 12 is a front elevational view of the form shown in FIG. 11;

FIG. 13 is a side elevational view of the form shown in FIG. 11;

FIG. 14 is a rear elevational view of the form shown in FIG. 11;

FIG. 15 is an elevational view of the left-hand end of the form shown in FIG. 11 drawn to an enlarged scale;

FIG. 16 is an elevational view of the right-hand end of the form shown in FIG. 11 drawn to an enlarged scale;

FIG. 17 is a cross-sectional view taken on the line 17—17 of FIG. 12 drawn to an enlarged scale; and

FIG. 18 is a cross-sectional view taken on the line 18—18 of FIG. 12 drawn to an enlarged scale.

This application is a continuation of our copending applications, Serial Nos. D. 86,229 and D. 86,231, each filed July 21, 1965, and each now abandoned.

We claim:

The ornamental design for an insulating support for electrical bus bars or similar article, substantially as shown and described.
